UNITED STATES PATENT OFFICE.

A J WOOD, OF GREENVILLE, MICHIGAN.

GREASE-GUN.

1,259,818.

Specification of Letters Patent. Patented Mar. 19, 1918.

Application filed February 27, 1917. Serial No. 151,202.

To all whom it may concern:

Be it known that I, A J Wood, a citizen of the United States of America, residing at Greenville, in the county of Montcalm and 5 State of Michigan, have invented certain new and useful Improvements in Grease-Guns; and I do hereby declare the following to be a full, clear, and exact description of the invention, such as will enable others 10 skilled in the art to which it appertains to make and use the same.

This invention relates to an appliance for handling greases and the like, especially those greases of a more or less heavy 15 consistency which are used in lubricating certain parts of the mechanism of motor vehicles such as the transmission and the differential gearing. It is the object and purpose of my invention to provide a device of this character of very simple structure and one which can be economically produced, the invention consisting in many 20 novel features of construction and arrangement of parts whereby the functions of the machine are efficiently attained. My invention 25 is illustrated in the accompanying drawing in which:

Figure 1 is a vertical section taken centrally through the device.

30 Fig. 2 is a plan view thereof.

Fig. 3 is a fragmentary vertical section taken through the lower part of the pump barrel and the coacting seat therefor and showing the relative position of the parts on 35 the upward stroke of the pump piston.

Figs. 4 and 5 are a plan and side view, respectively, of the seat member for the lower part of the pump barrel.

Like reference characters refer to like 40 parts throughout the several views of the drawing.

In the construction a receptacle 1 is provided having a bottom 2 the whole being supported by standards 3, the lower ends of 45 which are turned outward to make horizontal feet 4 against any one of which the foot of the operator may be placed when the device is operated. An opening is made in the bottom 2 above which is located a member 5 having a relatively large head and a projecting screw threaded shank 6 which extends through the opening in and is secured to the bottom 2 by an elbow coupling 7 screwing on to shank 6. Washers 8 are in-

terposed between the head 5 and coupling 7 55 and the bottom 2 to make a grease tight connection. The free end of the elbow 7 has a flexible hose 9 connected thereto as shown.

The member 5 heretofore described is bored centrally the diameter of the bore at 60 its upper end being larger than at its lower end and an inclined seat 10 formed at the juncture of the two bores of different diameter. A rod 11 projects upwardly from member 5 and at its upper end is curved in 65 substantially circular form as shown at 12 making a guide for the lower part of a cylindrical barrel 13 which extends the full length of receptacle 1 and at its upper end passes loosely through a supporting bracket 70 14 connected to one side of the receptacle. A plug 15 closes the upper end of the barrel. Depending from the plug is a flexible member 16, preferably of spring steel, which at 75 its lower end is turned inwardly toward the barrel, forming a lip 17 as shown. A rod 18 having a handle 19 at its upper end passes through the plug 15, its lower end carrying a suitable valveless piston 20.

In operation, the receptacle being wholly 80 or partially filled with a grease and the piston 20 being at the lower end of the barrel as shown in Fig. 1, to obtain grease from the receptacle the operator places his foot on one of the members 4 and pulls upwardly 85 on the handle 19. The first effect is to elevate the barrel 13 until lip 17 engages against the bracket 14 the lower end of the barrel occupying substantially the position shown in Fig. 3 with an unobstructed space 90 between the lower end of the barrel and the member 5. With the continuation of the pull on handle 19, rod 18 and piston 20 are carried upwardly and the grease is drawn in by suction through this opening 95 below the barrel into the barrel. On the downward stroke the first movement that occurs is the dropping of the barrel so that its lower end seats against the conical seat 10 closing the opening between the barrel and 100 the member 5 whereupon the further movement of the piston 20 forces the grease outward through the hose 9 to any desired place.

Many changes in minor detail of structure and in the positioning of the barrel 13 with its associated mechanism may be made without departing from the invention. Ac-

cordingly, I do not wish to be limited to the exact structure shown but consider myself entitled to any and all modifications in structure which come within the scope of 5 the appended claims defining the invention.

I claim:—

1. A device of the character described, including a receptacle, a member having a 10 passage therethrough secured in the bottom of the receptacle, a conduit connected to and leading away from said member, a barrel loosely mounted above said member, a valveless piston in the barrel, means for 15 raising and lowering the piston, said barrel being elevated with said raising and returned to lower position on said lowering of the piston, a tapered seat on said member for the lower end of the barrel, a guide 20 means connected to said member and associated with the lower end of the barrel to guide the same into engagement with the seat, and means limiting the upward movement of the barrel, substantially as described. 25

2. A device of the character described, including a receptacle, a bracket secured to and extending inwardly from a wall of the receptacle adjacent its upper end, a member 30 having a passage therethrough secured on the bottom of the receptacle, a barrel passed loosely through the bracket and having its lower end normally entered into said passage, a conical tapered seat on the 35 member against which the lower end of the barrel normally engages, a plug closing the upper end of the barrel, a valveless piston in the barrel, a rod secured thereto extending through the plug, a handle on the upper 40 end of the rod, and a member secured at the upper end of the barrel extending downwardly for a distance and turned inwardly toward the barrel to form a stop to engage

against the bracket on upward movement of the barrel, substantially as described. 45

3. A device of the character described including a receptacle, a barrel loosely mounted therein; guides for the upper and lower ends of the barrel, a conical tapered seat for the lower end of the barrel, means for limiting the upward movement of the barrel, a bottom to the receptacle having an opening therethrough in alignment with the interior of the barrel, a flexible hose in communication with said opening, a piston in the 55 barrel, and means for operating the piston, substantially as described. 50

4. A device of the character described including a receptacle, a bottom to the receptacle having an opening therein, a member having an enlarged head and a threaded shank, the shank passing downwardly through said opening, said member being 60 interiorly bored, with the boring at the upper end of larger diameter than at the 65 lower end and an annular inclined seat connecting the borings, a cylindrical barrel normally entered into the upper part of said member and resting at its lower end on said seat, a guide carried by said member 70 loosely passing around the lower part of the barrel, an elbow coupling screwed on to the shank of the member, a flexible hose connected to the coupling, a bracket secured adjacent the upper part of the receptacle 75 through which the barrel loosely passes, a plug closing the upper end of the barrel, a piston in the barrel, a rod connected thereto passing through the plug, a handle on the upper end of the rod, and a member 80 connected to the plug extending downwardly alongside the barrel for a distance and turned inwardly toward the barrel at its lower end.

In testimony whereof I affix my signature. 85
A J WOOD.
